INVENTOR,

H. Hunt

United States Patent Office.

H. HUNT, OF DELAVAN, WISCONSIN.

Letters Patent No. 72,495, dated December 24, 1867.

IMPROVEMENT IN GATES.

The Schedule referred to in these Letters Patent and making part of the same.

TO ALL WHOM IT MAY CONCERN:

Be it known that I, H. HUNT, of Delavan, in the county of Walworth, in the State of Wisconsin, have invented an Improved Gate; and I do hereby declare that the following is a full and exact description thereof, reference being had to the accompanying drawings, and to the letters of reference marked thereon, making a part of this specification, in which—

Figure 1 is an elevation of my gate.

Figure 2 a plan view of the same, with the cap removed to give a clear understanding of its construction.

Figure 3, a perspective representation of the pulleys over which the cords operating the gate are made to work.

The nature of my invention relates to that class of gates designed more especially for carriage-ways, and for other purposes, where it is desirable for the driver to open and shut the gate without dismounting; and its nature consists in supporting the gate on a compound inclined plane, by means of common friction-rollers, whereby it may more readily incline to open or shut, as the case may require, and in the use of a series of upright and horizontal pulleys, over which cords are made to pass and sustain weights for balancing the gate, and assisting in controlling it when in use.

In order to give a correct understanding of my invention, I have marked corresponding parts with similar letters, and will now give a detailed description.

A I D represent the gate-posts, set in the ground or otherwise, in the usual manner, for the support of gate L, figs. 1 and 2; the posts I I being set such a distance apart as is suitable for said gate to pass between them when being opened and shut. A compound inclined plane, F E, is secured to posts I D A, and arranged to give motion to gate L, and control its force, by means of a curve, Z, made on the outer end of the post E, as seen at fig. 1. This curve, Z, is very important in preventing the gate from having too great a concussion against post D, and is therefore considered new and useful. The inclined planes F E, of themselves, are not considered new, they having been used before, but are used simply to make the gate operate.

An important part of my invention consists in arranging the pulleys J K, and fitting them to operate on a bracket, H, attached to the posts I I, and a cap, c. By means of this arrangement the pulleys are made to rest on an ornament and brace, which can be readily detached for the purposes of transportation and repairs. The posts B, having arms, S, are set such a distance from gate L as is most convenient for a person sitting in a carriage to pull down on weights X. Two ropes, m m, are attached to a draught-cord, n, and made to pass between J K, and then over pulleys r r, made to run on arms S, figs. 1 and 2, by which means the gate is moved. The draught-cord n is made fast to the stiles of gate L at O P, and is drawn tightly around said stiles for the purpose of applying the power for moving the gate directly against the opposite side to that course or direction the gate is being moved. This arrangement I consider important, as it strengthens the gate and prevents it from being drawn apart by use.

Having thus fully described my device, I do not claim a gate hung on inclined planes, nor made to run thereon; but

What I do claim, and desire to secure by Letters Patent, is—

The arrangement and combination of pulleys J K, attached to bracket H, with cords n and m m, used for operating gate L, on planes F E, the latter having a curve, Z, substantially as set forth.

H. HUNT.
